[57] CLAIM

The ornamental design for a jewelry armoire, as shown and described.

DESCRIPTION

FIG. 1 is a perspective view of a jewelry armoire showing our new design;

FIG. 2 is a left side elevational view, the right side being a mirror image thereof;

FIG. 3 is a top plan view thereof;

FIG. 4 is a front perspective view with the side doors and lid open for convenience of illustration; and,

FIG. 5 is an enlarged fragmentary perspective view of the decorative band of the armoire.
